ATTORNEY

UNITED STATES PATENT OFFICE

GEORGE LAING, OF CALGARY, ALBERTA, CANADA

ATTACHMENT FOR SOUND-REPRODUCING MACHINES

Application filed February 26, 1929, Serial No. 342,860, and in Canada July 20, 1928.

This invention relates to an attachment for use in connection with sound reproducing machines of various kinds and classes and particularly to the cabinets or casings of such machines; and the object of the invention is to provide an attachment of the class specified, with simple means for coupling and mounting the same in connection with the cabinet in such manner as to arrange the same in the path of the sound transmitting passage or discharge of the machine so as to convey a stage-like setting; a further object being to provide the attachment with an adjustable or movable screen arranged as a closure for said discharge opening but of such a nature as to not materially interfere with the transmission of sound therethrough; a further object being to provide means for eliminating the stage representation or chamber of the attachment in pleasing color effects; and with these and other objects in view, the invention consists in a device of the class and for the purpose specified which is simple in construction, efficient in use and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a front elevation of the attachment, part of the construction being broken away and in section.

Fig. 2 is a sectional, plan view taken on the line $x-x$ of Fig. 1.

Fig. 3 is a sectional side elevation; and,

Fig. 4 is a side elevation showing part of a gramophone or other apparatus in section.

In the accompanying drawings, 1 represents the attachment proper which as will be seen, is in the form of a miniature stage, adapted to be supported in connection with a gramophone 2 or the cabinet or casing of other reproducing or transmitting apparatus of any kind or class. At 3 and 4, I have shown two doors hinged to the casing 2 at opposite sides of an opening 2a formed therein, through which opening, the sound or

tone transmitted from the apparatus is adapted to pass.

Hook-shaped supporting brackets 5 and 6 are adjustably supported in connection with the side walls 7 and 8 of the attachment 1, and said walls are preferably inclined backwardly to form a narrower rear end portion as clearly seen in Fig. 2 of the drawing. The brackets are adapted to hang over the top edges 9 and 10 of the doors as clearly seen in Figs. 1, 2 and 4 of the drawing. Arranged at the back of the attachment is a screen 12 which is mounted upon rollers 13 and 14 located in the upper and lower portions of the attachment, said screen being capable of upward and downward movement by the rotation of knobs 15 and 16 provided at one end of each roller.

With this construction, a pleasing, appropriate or harmonizing scene printed, painted or otherwise applied to the screen may be brought to view within the cabinet or at the rear portion of the stage representation formed thereby. This scene may be varied from time to time to be consistent with the music or other selection played by the apparatus in connection with which the attachment is employed.

I also preferably arrange at the top 17 of the attachment, a plurality of electric bulbs 80 preferably of different colors in order to provide different color effects, the electrical connections and control being cared for along conventional lines. A plurality of small holes 18 are also preferably formed in the frieze of the entablature at the front of the attachment to allow the heat from the bulbs to pass through the same and at the same time to form small lights in front of the stage.

Portable figures or scene pieces such as indicated at 19 may be used upon the stage to increase the attractiveness of the stage setting, and again, these figures are preferably consistent with the selection or reproduction which is transmitted from the apparatus in connection with which the attachment is employed.

It will be understood that my invention is not necessarily limited to the specific, struc-

tural details herein shown and described, nor to the manner of supporting or arranging the attachment, and various other changes in and modifications of the construction herein shown and described may be made within the scope of the appended claims, without departing from the spirit of my invention or sacrificing its advantages.

Having fully described my invention, 10 what I claim as new and desire to secure by Letters Patent, is:—

1. An attachment in combination with gramaphones and other musical devices, constructed to rest and lie between the doors of 15 the same when open, the attachment having hooks or supports to fit and take the top edge of the doors, a screen having scenes thereon, said screen being carried by rollers, the screen being capable of movement to change the 20 scenes, substantially as set forth.

2. An attachment in combination with gramaphones and other musical devices constructed to rest and lie between the doors of the same when open, the attachment having 25 hooks or supports to fit and take the top edges of the doors, a screen having scenes thereon, said screen being carried by rollers, the screen being capable of movement to change the scenes as desired, lighting arrangement for 30 different colored lights, holes in the front of the attachment, all substantially for the purpose as set forth.

3. An attachment formed as a stage in combination with gramaphones and other musical devices constructed to rest and lie between the doors of the same, hooks or supports to fit and take the top edge of the doors, a screen having scenes thereon, said screen being carried by rollers, the screen being capable of 35 movement to change the scenes, lighting arrangement for different colored lights, all as a stage setting for the purpose of conveying to an audience the atmosphere of the theatre 40 substantially as described and set forth.

4. An attachment formed as a stage setting, means for detachably supporting said attachment in connection with a sound reproducing apparatus to arrange the same in the path of the transmission of sound from 45 said apparatus, and said attachment including a shiftable scene element disposed in the path of said sound and through which the sound is free to pass.

5. An attachment formed as a stage setting, means for detachably supporting said attachment in connection with a sound reproducing apparatus to arrange the same in the path of the transmission of sound from 50 said apparatus, said attachment including a shiftable scene element disposed in the path of said sound and through which the sound is free to pass, said attachment comprising a 55 casing, the front and back walls of which are open, the front wall being characterized to

represent a stage, and means for illuminating the interior of said casing.

6. An attachment formed as a stage setting, means for detachably supporting said attachment in connection with a sound reproducing apparatus to arrange the same in the path of the transmission of sound from said apparatus, said attachment including a shiftable scene element disposed in the path of said sound and through which the sound is free to 70 pass, said attachment comprising a casing, the front and back walls of which are open, the front wall being characterized to represent a stage, and means for illuminating the interior of said casing and scene elements 75 supported within said casing.

In testimony that I claim the foregoing as my invention I have signed my name this 19th day of February, 1929.
